CLOTHESLINE

Juan Angel Torriente, Los Angeles, Calif.

Application February 6, 1956, Serial No. 563,616

3 Claims. (Cl. 211—124)

This invention relates to clotheslines and similar structures for supporting a flexible object in space, and more particularly to a clothesline which does not require the use of clothespins or the like to retain the object supported fixed in place.

In the ordinary clothesline it is conventional to clamp each article to the line with one or more separate clothespins. Each of these pins must be removed in order to remove the article from the line and they must be stored until the line is used again. It is an object of the invention to provide a clothesline which does not require the use of a plurality of separate clamps or pins to maintain articles in position on the line.

It is a further object of the invention to provide a clothesline having a relatively rigid longitudinal member for supporting the articles of clothing and a relatively flexible longitudinal member positioned adjacent the rigid member for retaining the articles in position on the rigid member, the two members being fastened together adjacent their respective ends. Another object of the invention is to provide such a clothesline having a spring structure which urges the flexible member into contact with the rigid member to retain the articles firmly in place.

Another object of the invention is to provide a clothesline with a rigid supporting member having a groove along the longitudinal axis thereof, and a second member adapted to fit into the groove to clamp an article of clothing between the members in a reverse curve, creating retaining forces without the use of separate pins or clamps.

The invention also comprises novel details of construction and novel combinations and arrangements of parts, which will more fully appear in the course of the following description. However, the drawings merely show and the description merely describes preferred embodiments of the present invention which are given by way of illustration or example only.

In the drawings:

Fig. 1 is an isometric view showing two embodiments of the invention on a single support structure;

Fig. 2 is an enlarged partially sectional view taken along the line 2—2 of Fig. 1;

Fig. 3 is a sectional view taken along the line of 3—3 of Fig. 2;

Fig. 4 is an enlarged sectional view taken along the line 4—4 of Fig. 1; and

Fig. 5 is an enlarged sectional view taken along the line 5—5 of Fig. 1.

In Fig. 1, two clotheslines embodying the features of the invention are shown mounted on a suitable support structure. The support structure includes a pair of horizontal bars 10, 11, the bar 10 being mounted on a vertical post 12 and the bar 11 being mounted on a similar vertical post (not shown). Brackets 13 are mounted at an angle between the horizontal bars and the vertical posts to give additional stability to the support structure. Two garment-supporting structures 14, 15 are mounted

2

on the bars 10, 11 parallel to each other. These two structures, 14, 15, employ two embodiments of the invention.

The structure 14 is the preferred embodiment and includes a beam 20 which is mounted on the bars 10, 11 by suitable means such as pins or screws (not shown), the beam 20 being made of wood, aluminum or other substantially rigid material. The beam may be permanently affixed to the bars 10, 11 or the components may 10 be assembled so that they are easily taken apart and stored when the clothing-drying structure is not in use.

A longitudinal groove 21 may be provided along the upper surface of the beam 20 and in the embodiment illustrated in Fig. 2 the groove is shown extending over the end 22 of the beam. A cable 23, which may be made of steel, aluminum, plastic, cotton, or other suitable material, is positioned along the upper surface of the beam 20 in the groove 21. A ferrule 24 having a hook 25 is attached to an end of the cable 23 and a second hook 26 is mounted on the bar 10. The hook 25 is connected to the hook 26 by a tension spring 27 and a turnbuckle 28, thereby providing an anchor for one end of the cable 23. A similar construction may be employed at the other end of the cable 23 or the spring 27 and the turnbuckle 28 may be omitted, the hooks 25 and 26 being directly engaged. The purpose of this construction is to stress the cable 23 in tension and urge the cable 23 against the surface of the beam 20.

When an article, such as a garment 30, is to be placed 30 on the clothesline, the cable 23 is lifted from contact with the beam 20 and the garment is inserted through the space between the cable and the beam. Then the cable 23 is released and because it is stressed in tension, the garment is firmly clamped between the cable and the beam as illustrated in Fig. 3. The garment may be removed by exerting a steady pull thereon, preferably in a horizontal direction, without the necessity of raising the cable 23 from the beam 20.

While the above described construction is the preferred embodiment of the invention, other forms of construction may be utilized in employing the features of the invention. For example, the cable 23 may be made of an elastic material such as rubber or even in the form of a long coil spring, thereby eliminating the need of the tension spring 27 at the end of the cable. In the preferred embodiment, the groove 21 is semicircular in shape and the cable 23 is circular. However, the cable could be made in other forms and the groove could have a corresponding shape. The groove serves to maintain the cable in position along the beam and it also provides for a firm grip on the garment due to the contours produced in the garment by the engagement of the cable with the groove.

In the structure 15 a second embodiment of the invention is shown. Therein a beam 20' is mounted on the bars 10, 11 in a manner similar to that of the beam 20. A flat strip 31 having a rectangular cross section and composed of an elastic material is positioned along the upper surface of the beam 20'. The strip 31 is terminated with a flat block 32 having a vertical opening therethrough. A substantially Z-shaped rod 33 having one end projecting through the opening in the block 32 and the other end engaged in a suitable opening in the beam 20' anchors the end of the strip 31 to the beam. The tension in the strip 31 may be adjusted by providing a plurality of spaced openings in the block 32. One such opening is indicated by the numeral 32'.

A spacer may be provided to facilitate lifting the cable 23 out of the groove 21 when it is desired to place an article on the clothesline. A spacer rod 34 is mounted in a handle 35, the rod 34 being bent to wrap around the beam 20 (Figs. 1 and 4). The top portion

36 of the rod is inserted between the cable 23 and the beam 20 and since the rod is rigid it spaces the cable from the beam, lifting the cable out of the groove and making it easily grasped by the fingers. The rod is slideable along the beam and should be moved along the beam from one end to another as articles are placed on the beam. A groove 37 may be made in the beam transverse to the longitudinal axis thereof and preferably adjacent to one end of the beam as shown in Fig. 2. This groove provides a resting place for the spacer rod 34 so that the rod may be left on the beam at all times without affecting the clamping pressure between the cable 23 and the beam 20.

Although several exemplary embodiments of the invention have been disclosed and discussed, it will be understood that other applications of the invention are possible and that the embodiments disclosed may be subjected to various changes, modifications and substitutions without necessarily departing from the spirit of the invention.

I claim as my invention:

1. In a clothesline, the combination of: a substantially rigid beam adapted for mounting in a horizontal position with an upwardly facing surface, said surface having a groove therein extending the length of said beam; a flexible member disposed along said surface in said groove; resilient means coupling said flexible member to said beam adjacent each end thereof and urging said flexible member into said groove; and a spacer disposed

laterally between said surface and said flexible member and movable longitudinally along said beam for lifting said member from said groove.

2. In a clothesline, the combination of: a bar having a longitudinal groove along the top surface thereof; support means maintaining said bar relatively horizontal; cable means lying in said groove, the ends of said cable means being fixed relative to said bar, said cable means including spring means stressing said cable means in tension and urging said cable means into said groove; and hook means laterally positioned between said bar and said cable means and formed so as to engage all sides of said bar, said hook means being movable longitudinally along said bar, said hook means maintaining adjacent portions of said cable means out of said groove.

3. A clothesline as defined in claim 2, including at least one lateral groove along said top surface, said lateral groove being capable of receiving said hook means and deep enough to place said hook means below said top surface.
